UNITED STATES PATENT OFFICE.

ROLANDIS A. BLAIR, OF FORT WAYNE, INDIANA, ASSIGNOR TO THE P. & M. COMPANY, OF CHICAGO, ILLINOIS, A CORPORATION OF ILLINOIS.

RAIL ANCHOR.

Application filed May 12, 1923. Serial No. 638,490.

My invention relates to devices for preventing the longitudinal creep of railroad rails, these devices being commonly called rail anchors, anti-creepers, or rail stays.

One of the objects of my invention is the provision of a rail anchor of simple and compact construction, inexpensive to manufacture, which will maintain a reliable hold on the rail as against the tendency of the device to become loosened by vibration or other disturbing influences, and which may be quickly and conveniently put in place on the rail, or removed therefrom, if occasion requires.

15 A further object of my invention is the provision of a rail anchor which can be used with rails, the bases of which are of different width or of different contour.

It is a further object of my invention to 20 provide a rail anchor so constructed that it may be removed and replaced several times without impairing its holding power.

The invention consists in the novel arrangements and constructions to be herein- 25 after described and claimed for carrying out the above-stated objects and such other objects as will appear from the following description of a preferred embodiment illustrated in the accompanying drawings,

30 wherein—

Fig. 1 is a side elevational view of a device embodying the principles of my invention and applied to a section of rail;

Fig. 2 is a plan view of the device in position on the rail; and

Fig. 3 is a perspective view of the device.

Like characters of reference designate like parts in the several views.

40 Referring now to the drawings, the embodiment therein illustrated is formed from a slightly resilient steel bar, rectangular in cross-section, which is formed or bent so as to provide a jaw 5 adapted to extend around and over one of the rail base flanges, for example, the flange 6, a medial portion 7 adapted to extend substantially transversely under the rail base, a shoulder 8 adapted to engage the edge of the rail base flange 9, and a downwardly extending foot-piece 10 adapted to bear against the side of a tie 11.

The device is applied to the rail by slipping the foot-piece 10 and the adjacent end of the medial portion 7 under the rail base 55 and hooking the jaw 5 over one of the base

flanges. The outer end of the jaw is then struck with a sledge and the device is driven transversely of the rail until the shoulder 8 comes into alignment and snaps into engagement with the edge of the other 60 base flange. The jaw 5 and the medial portion 7 are so formed in relation to each other that the distance between the under surface 5^a of the jaw and the top surface of the medial portion, when the device is free of the rail, is considerably less than the thickness of that part of the base flange which lies between said surfaces when the device is in position on the rail.

The jaw 5, therefore, must be sprung or 70 forced away from the medial portion 7 when the device is applied to the rail; consequently the jaw 5 exerts a strong downward pressure against the top of the base flange and the medial portion a strong up- 75

ward pressure against the bottom of the rail base. Since the medial portion 7 is held with its top surface bearing firmly against the bottom of the rail base, the shoulder 8 is maintained in effective holding engage- 80

ment with the edge of the flange 9; consequently, the device cannot move transversely of the rail in the reverse direction to free itself. The tendency of the device to return to its original shape results in a strong, 85 reliable gripping action on the rail base which is ample to prevent any slippage of the device longitudinally of the rail, notwithstanding the disturbing influences to which the device is subjected due to the passage of heavy rolling stock and weather conditions.

The jaw 5 is so formed that a clearance is provided between the inner side of said jaw and the adjacent edge of the base flange 6. 95 The tendency of the jaw extremity to remain relatively close to the top surface of the medial portion 7 is great enough to make it possible to apply the device to rail bases relatively narrow in width as well as to rail 100 bases of substantially greater width, also to rails having different base contours and those of which the base flanges vary in thickness.

The foot-piece 10 is preferably formed on that end of the device which is opposite the 105 jaw 5; consequently, the device, when under a creeping strain, is subjected to a skewing action which increases the grip of the device on the rail. The foot-piece is also preferably so positioned that its tie engaging face is 110

considerably forward of the forward side 7* of the medial portion 7, having reference to the direction of creepage which is indicated by the arrow Fig. 2; therefore, the skewing 5 action referred to is obtained before any portion of the forward side of said medial portion can bear against the tie.

The medial portion 7, intermediate the shoulder 8 and the jaw 5, is formed so as to 10 provide a rearwardly extending portion 12 the top of which bears against the bottom of the rail base. The portion 12 effectively prevents any rocking or tilting of the device on the rail.

15 The device is of simple and compact construction and inexpensive to manufacture. It may be readily removed from the rail by prying down the end opposite the jaw and then driving the device transversely from the 20 rail base. After having been removed, it may again be applied to the rail.

I do not intend to limit my invention to the details of construction shown and described, except only in so far as certain of 25 the appended claims are specifically so limited, as it will be obvious that modifications may be made without departing from the principles of my invention.

I claim:

30 1. A device for preventing the longitudinal creep of railroad rails comprising means extending substantially transversely under the rail base, a jaw on one end of said means and adapted to extend around and over one 35 of the rail base flanges, said jaw and means being so formed in relation to each other that said means exerts an upward pressure against the bottom of the rail base and said jaw a downward pressure against the top of 40 said flange when the device is applied to the rail, a shoulder on the other end of said means and adapted to engage the edge of the other rail base flange, a tie abutting portion depending from said means, and a portion 45 extending from said means rearwardly with respect to the direction of creepage and adapted to bear against the bottom of the rail, for the purpose described.

2. A device for preventing the longitudinal 50 creep of railroad rails comprising means extending substantially transversely under the rail base, a jaw on one end of said means and adapted to extend around and over one 55 of the rail base flanges, said jaw and means being so formed in relation to each other that said means exerts an upward pressure against the bottom of the rail base and said jaw a downward pressure against the top of said flange when the device is applied to the rail, a shoulder on the other end of said means and adapted to engage the edge of the other rail base flange, a tie abutting portion depending from said means, at a point adjacent said shoulder, and a portion extending from said means rearwardly with respect

to the direction of creepage and adapted to bear against the bottom of the rail, for the purpose described.

3. A device for preventing the longitudinal creep of railroad rails comprising 70 means extending substantially transversely under the rail base, a jaw on one end of said means and adapted to extend around and over one of the rail base flanges, said jaw and means being so formed in relation to 75 each other that said means exerts an upward pressure against the bottom of the rail base and said jaw a downward pressure against the top of said flange when the device is applied to the rail, a shoulder on the other end 80 of said means and adapted to engage the edge of the other rail base flange, a foot-piece depending from said means at a point adjacent said shoulder, the tie engaging face of said foot-piece being in a plane substantially 85 forward of the adjacent vertical side of said means, and a portion extending from said means rearwardly and adapted to bear against the bottom of the rail, for the purpose described.

4. A one-piece device for preventing the longitudinal creep of railroad rails, comprising 90 a metal bar formed so as to provide a jaw adapted to extend around and over one of the rail base flanges, a medial portion adapted to extend substantially transversely under the rail base, a shoulder adapted to engage the edge of the other rail base flange, and a downwardly extending foot-piece connected with the medial portion adjacent to said shoulder, said jaw and medial portion being so formed in 95 relation to each other that said medial portion exerts an upward pressure against the bottom of the rail base and said jaw a downward pressure against the top of the flange adjacent thereto when the device is applied to the rail, the tie engaging face of said foot-piece being in a plane substantially forward of the adjacent vertical side of said medial portion with respect to the direction of creepage, for the purpose described.

5. A one-piece device for preventing the longitudinal creep of railroad rails, comprising 100 a metal bar formed so as to provide a jaw adapted to extend around and over one of the rail base flanges, a medial portion adapted to extend substantially transversely under the rail base, a shoulder adapted to engage the edge of the other rail base flange, and a downwardly extending tie abutting portion, said jaw and medial portion being 105 so formed in relation to each other that said medial portion exerts an upward pressure against the bottom of the rail base and said jaw a downward pressure against the top of the flange adjacent thereto when the device is applied to the rail, said medial portion being bent to provide a portion extending rearwardly, with respect to the direction 110

of creepage, and adapted to bear against the bottom of the rail, for the purpose described.

6. A one-piece device for preventing the longitudinal creep of railroad rails, comprising a metal bar formed so as to provide a jaw adapted to extend around and over one of the rail base flanges, a medial portion adapted to extend substantially transversely under the rail base, a shoulder adapted to engage the edge of the other rail base flange, and a downwardly extending tie abutting portion adjacent said shoulder, said jaw and medial portion being so formed in relation to each other that said medial portion exerts an upward pressure against the bottom of the rail base and said jaw a downward pressure against the top of the flange adjacent thereto when the device is applied to the rail, said medial portion being bent to provide a portion extending rearwardly, with respect to the direction of creepage, and adapted to bear against the bottom of the rail, for the purpose described.

7. A one-piece device for preventing the

longitudinal creep of railroad rails, comprising a metal bar formed so as to provide a jaw adapted to extend around and over one of the rail base flanges, a medial portion adapted to extend substantially transversely under the rail base, a shoulder adapted to engage the edge of the other rail base flange, and a downwardly extending foot-piece adjacent said shoulder, said jaw and medial portion being so formed in relation to each other that said medial portion exerts an upward pressure against the bottom of the rail base and said jaw a downward pressure against the top of the flange adjacent thereto when the device is applied to the rail, the tie engaging face of said foot-piece being in a plane substantially forward of the adjacent vertical side of said medial portion, said medial portion being bent to provide a portion extending rearwardly and adapted to bear against the bottom of the rail, for the purpose described.
